REFRIGERATING APPARATUS

George C. Pearce and Albert O. Grooms, Dayton,
Ohio, assignors to General Motors Corporation,
Dayton, Ohio, a corporation of Delaware

Application May 31, 1941, Serial No. 395,934

7 Claims. (Cl. 62—4)

This invention relates to refrigerating apparatus and more particularly to control means therefor.

When the load is light it is found desirable to operate heating and cooling systems at a reduced capacity. To accomplish this two separate, accurately matched thermostats have been used. However, such thermostats provide no means for varying the difference between the two thermostats according to the season or other conditions.

It is an object of our invention to provide a single control for controlling two functions consecutively with means for varying both functions together, and also relative to one another.

It is another object of our invention to provide a control with an improved adjusting and indicating device in which more than one revolution of the adjusting device can be provided within the limits of the indicator.

It is another object of our invention to provide a means for reducing the inherent differential of cycling in refrigeration controls.

Further objects and advantages of the present invention will be apparent from the following description, reference being had to the accompanying drawings, wherein a preferred form of the present invention is clearly shown.

In the drawings:

Fig. 1 is a view partly diagrammatic of a cooling system provided with a control embodying one form of our invention;

Fig. 2 is a wiring diagram for the control and system shown in Fig. 1;

Fig. 3 is a sectional view of the control taken along the line 3—3 of Fig. 4;

Fig. 4 is a sectional view taken along the line 4—4 of Fig. 5;

Fig. 5 is a sectional view taken along the line 5—5 of Fig. 4;

Fig. 6 is a sectional view taken along the line 6—6 of Fig. 4;

Fig. 7 is a vertical sectional view through the adjusting knob; and

Fig. 8 is a fragmentary top view of the adjusting mechanism and a dial with the knob removed.

Briefly, we have shown a heat exchange system with a control for operating the system at either part load or full load in accordance with the demand. The control is provided with a single operating means in accordance with temperature which operates two snap-acting devices having independent differential adjustments. The operating means is directly connected to one lever operating one of the snap-acting devices while this one lever is connected through an adjust-

able connection to operate a second lever which in turn operates the second snap-acting device. The control is also provided with an additional operating bulb for anticipating a change in temperature to reduce the overall differential of the system.

For the purpose of illustrating one application of our improved form of control, we have shown a refrigeration air conditioning system including a compressor 20, driven by an internal combustion engine 22 for withdrawing the evaporated refrigerant from an evaporating means 24 through a suction conduit 26 and for forwarding the compressed refrigerant to a condenser 28 where the compressed refrigerant is liquefied and returned to the evaporator 24 through the supply conduit 30 under the control of a suitable liquid control device 32. The evaporating means 24 is located within an air duct 34 which discharges into a room 36 or other enclosure to be kept cool. The air is drawn into the duct at its entrance end 38 by an electric fan 40 which forces the air through the evaporating means 24 so that it is cooled.

For controlling the operation of the refrigerating system, we provide a suitable control device 42 which is principally responsive to the air within the enclosure 36. This control device includes a base 44 carrying a bellows 46 which operates a lever 50. The expansion of the bellows is controlled by a compression type coil spring 52 which has its tension adjusted by a suitable adjusting screw 54 which is rotated by an adjusting knob 56. Heretofore in order to prevent the control becoming out of adjustment by the unrestricted adjustment of the knob it has been customary to limit the adjustable movement of the knob to one revolution. This has made the adjustment either very limited in range or very coarse. In order to provide a greater range and yet permit a fine adjustment, we have provided a means by which the knob 56 may be adjusted several revolutions without its adjustment being lost and retaining at all times an indication of its adjusted position.

In order to do this, we have provided a movable indicating plate 58 which is connected to the adjusting screw 54 and the knob 56 through a form of gearing so that it will be limited in movement to one revolution while the knob 56 may make two revolutions or more. As will be best seen in Figs. 7 and 8 the upper end of the screw 54 is provided with the splined end 60 which may be fastened to the shank of the screw 54 by riveting. The knob 56 is locked to the splined end

by a set-screw 62. The dial plate 58 is provided with a planetary pinion 64 which is rotatably mounted upon a rivet 66 fastened to the dial plate 58. This planetary pinion 64 meshes with the lower end of the splined portion 60 and also with an internal gear 68 which is fastened by the rivets 70 to the upper part of the switch frame member 72. The internal gear 68 is provided with a segment 74 which is not provided with teeth so that the revolving movement of the pinion 64 is stopped when it strikes either end of the segment 74. As shown the splined end 60 is provided with twelve teeth and the internal gear 68 with 42 teeth. This will allow the knob 56 to rotate several times during the revolving of the pinion 64 from one end of the internal gear 68 to the other. The dial plate 58 is provided with a suitable arrow 76 indicating the adjustment of the control by the knob 56. This arrow may cooperate with suitable legends provided upon the outer case 78 of the switch mechanism.

This control differs from ordinary controls in that a second lever 80 is connected to the usual lever 50. This connection is made by an arm 82 which is fastened to the lever 50 and extends over the second lever 80. The connection between the arm 82 and the lever 80 is made by a screw 84 which extends through an aperture in the arm 82 and threads into a threaded aperture in the lever 80. A compression type coil spring 86 is provided for keeping the arm 82 in engagement with the head of the screw 84. The screw 84 may be turned to bring the lever 80 closer or farther away from the arm 82 so as to change the relative positions of the levers 80 and 50.

Each of the levers are connected to identical snap-acting switch mechanisms. For this reason a detailed explanation will only be made for one switch mechanism. This connection is made by a molded member 88 which is provided by the free end of the lever 50 and which supports a double spring anchoring member 90. A pair of tension type coil springs 92 and 94 connect the anchoring member 90 with ears 96 and 98 provided upon opposite sides of a metal member 101 having its opposite end riveted by an electrical contact member 103 to the free end of a flexible metal strip 105 having its opposite end anchored to a post 107. The springs 92 and 94 together with the members 101 and 105 form an excellent toggle snap-acting device having high current-carrying capacity. The differential of the toggle mechanism is controlled by a set screw 109 which controls the open position of the contact 103 while the closed position is controlled by the location of the contact post 111. An arm 113 is provided for limiting the movement of the member 101.

The snap-acting device connected to the lever 80 is identical and is also provided with a differential adjusting screw 115. Thus the differential of the two snap-acting devices may be adjusted by their respective screws 109 and 115 independently of each other so that their differentials may be made either the same or different as desired within the limits of the device. The screw 84 may be adjusted so as to vary the relative position of the two levers as desired. If the differentials are the same the screw 84 may be adjusted so that both switches will open and close at the same time or so that one of the switches will precede or succeed the operation of the other by any desirable amount of movement of the operating bellows 46. This same thing can also be done when the screws 109 and 78

115 are adjusted to two different differentials. In such a case, the screw 84 can be adjusted so that one of the points of operation of one of the switches may coincide with a point of the operation of the other of the switches. Also the range of one of the switches may be either within or without the range of the other of the switches. It will therefore be seen that there is provided free flexibility in the control and adjustment of this control device.

The bellows 46 is connected by a suitable tube 117 to a bulb 119 mounted in the incoming air stream of the duct 34 so that it is substantially responsive to the temperature of the air within 15 the enclosure 36. Preferably this bulb is filled with activated charcoal and the entire system is charged with methyl chloride or some other suitable gas which is adsorbed and evolved from the activated charcoal in the bulb 119 according 20 to changes in temperature. The vapor pressure of the methyl chloride should be sufficiently low to prevent free condensation at any point. However, the control 42 may be operated by any 25 sort of operating device operating in accordance with any volume which is the source of control.

We have found that snap-acting devices, though desirable for effecting the operation of switch mechanisms, have a larger differential than is desirable for some refrigeration applications. It is difficult to reduce the differential of snap-acting mechanisms below a certain optimum without incurring certain disadvantages. We have discovered that if an additional bulb 121 is placed in the air stream flowing away from 35 the evaporating means 24, the overall differential may be reduced without changing the differential of the snap-acting mechanisms. This additional bulb 121 is filled with the same material as the other bulb 119, such as activated charcoal and 40 the methyl chloride or other gas used. This methyl chloride or other gas flows to and from the bulb 121 as well as to the remaining points of the system.

In operation the bulb 119 always follows the 45 temperature of the enclosure 36 as accurately as possible. The bulb 121 when the refrigerating system is in operation is cooled below the temperature of the enclosure. When the refrigerating system is not in operation the bulb 121 returns to substantially the temperature of the air in the enclosure 36. In order to effect the 50 operation of the switch mechanism from open position to closed position a predetermined volume of gas must be forced into the bellows 46. This is accomplished by a rise in temperature of both bulbs 119 and 121 in accordance with the rise in temperature within the closure 36. This rise in temperature of the bulbs 119 and 121 drives a certain amount of methyl chloride out 55 of the activated charcoal in the bulbs in accordance with the amount and quality of the activated charcoal present in each. When this temperature rise is sufficient the bellows 46 will operate one or both switch mechanisms in accordance with the adjustment of the device.

In the wiring diagram shown in Fig. 2, the fan 40 is shown connected across the supply conductors 123 and 125 which connect to opposite sides of a battery 127 or some other suitable 70 source of current supply. This fan motor is controlled by a manual switch 129 which also directly or indirectly controls the operation of the other electrical devices of the entire system. A second manual switch 131 controls the operation of the remaining devices in the electrical system as long

as the fan motor operates. The control device is illustrated in the wiring diagram by the contacts 111 and 103 operated by the lever 50 and the contacts 133 and 135 which are operated by the lever 80 (see Fig. 4).

It is intended that the screw 84 be so adjusted that the contacts 111 and 103 will be closed at a temperature which will require a relatively small amount of cooling such as one-third or one-half of full refrigerating capacity. For example, these contacts 111 and 103 may be set so that they will close at a temperature of 75° and open at a temperature of 73°. The screw 84 may be so adjusted that the contacts 133 and 135 will close when the temperature reaches 78°. The closing of the contacts 111 and 103 will close the ignition circuit of the internal combustion engine 22 including the ignition coil 137 and the distributor 139. It will also close the circuit through the relay 141 which will close a starting switch 143 to energize the starting motor 145 to start the internal combustion engine 22. Connected in series with the starting relay 141 is a suitable automatic switch 147 which will de-energize the starting motor 145 whenever the engine is in normal operation. Thus the closing of the contacts 111 and 103 insures the operation of the internal combustion engine 22 which drives the compressor 20.

The internal combustion engine 22 is provided with an electrically controlled throttle 149 which, when deenergized, causes the internal combustion engine 22 to be throttled and operate at a reduced speed supplying refrigeration at a reduced capacity. When the refrigeration load increases the bellows 46 will expand further to cause the closing of the contacts 133 and 135 to energize the electrically operated throttle 149 to fully open the throttle of the internal combustion engine so as to cause it to operate at full speed. Should this reduce the temperature sufficiently, the contacts 133 and 135 will open thereby reducing the speed of the internal combustion engine. In normal operation, the internal combustion engine under heavy loads will cycle between full load and part load while under light operating conditions it will cycle between a part load and a stopped condition.

When the refrigerating system operates the bulb 121 will be cooled below the temperature of the bulb 119 and the average air temperature within the enclosure 36. This additional cooling of the bulb 121 tends to reduce the overall differential of the control mechanism since it will reduce the amount of free methyl chloride in the actuating system below the amount which would be there at the actual air temperature of the enclosure. Therefore this excess cooling of the bulb 121 will provide the same effect as cooling the bulb 119 a certain amount below the actual temperature of the room prior to any actual reduction of the temperature of the room or enclosure. However, since the bulb 119 is actually at the same temperature as that of the room its temperature will fall as the room temperature falls; but as soon as the bulb 121 has been immediately cooled a certain sizeable amount by the effect of the cooled air coming directly off the evaporator 24, a much smaller amount of cooling of the bulb 119 will be required before the bellows 46 has contracted an amount sufficient to overcome the differential of the switch mechanism to open the contacts. By properly proportioning the amount of charcoal in the bulb 121 to the entire volume in the bulb system as

much of the differential can be removed as desired.

While the form of embodiment of the invention as herein disclosed, constitutes a preferred form, it is to be understood that other forms might be adopted, all coming within the scope of the claims which follow.

What is claimed is as follows:

1. A control including an operating means, a control device connected to and operated by the operating means, an adjustment means for the control including a manipulating means, an indicating means, a direct ratio speed changing device operatively connecting the manipulating means and the indicating means to provide movements of the indicating means corresponding in a direct ratio to the movement of the manipulating means, and means for limiting the movement of the indicating means.
  2. Refrigerating apparatus including a cooling unit, supply means for supplying a cooling medium to the cooling unit, cyclical control means having an inherent differential for cyclically controlling said supply means, means for circulating a medium to be cooled in heat exchange relation with the cooling unit, means responsive primarily to the temperature of the medium flowing to the cooling unit for controlling said cyclical control means, and means responsive primarily to the medium flowing away from the cooling unit for reducing the inherent differential of the cyclical control means.
  3. Refrigerating apparatus including a cooling unit, supply means for supplying a cooling medium to the cooling unit, cyclical control means having an inherent differential for cyclically controlling said supply means, means for circulating a medium to be cooled in heat exchange relation with the cooling unit, a fluid motor for operating the cyclical control means, a main bulb means responsive primarily to the medium flowing to the cooling unit, a compensating bulb means responsive primarily to the medium flowing away from the cooling unit for reducing the inherent differential of the cyclical control means, means connecting said bulb means with said motor, and means within the bulb means, connecting means and said motor for creating pressures therein substantially in accordance with the volume and temperature of the bulb means.
  4. A control including an operating means, a control device connected to and operated by the operating means, an adjustment means for the control including a manipulating means, an indicating means, direct ratio speed reducing planetary gearing operatively connecting the manipulating means and the indicating means to provide movements of the indicating means corresponding in a direct ratio to the movement of the manipulating means, and means for limiting the movement of the indicating means.
  5. Refrigerating apparatus for an enclosure containing a medium to be cooled comprising a cooling unit for cooling said medium, supply means operable at part load and full load for supplying a cooling fluid to said cooling unit, and control means including means responsive primarily to the temperature of the medium in said enclosure and also means cooled by said cooling unit for varying the operation of said supply means between part load and full load.
  6. A control including a single operating fluid motor, a first lever operated by said motor, a first toggle snap-acting means operated by said
- 75

first lever and having critical opening and closing points, means for adjusting said first toggle means to vary one of said points independently of the other, a second lever having its pivot substantially in alignment with the pivot point of the first lever, a second toggle snap-acting means operated by said second lever and having critical opening and closing points, means for adjusting said second toggle means to vary one of said points independently of the other, a first control device operated by said first toggle means, a second control device operated by said second toggle means, connecting means between the two levers, means for adjusting the connecting means to vary the relationship between the levers to vary the relationship between the operation of the control devices, and adjustable spring means acting upon said fluid motor to vary the relationship between the pressure within the fluid motor and the operation of the control devices.

7. Refrigerating apparatus for an enclosure containing a medium to be cooled comprising a cooling unit for cooling said medium, supply

means for supplying a cooling fluid to said cooling unit, cyclical control means for cyclically controlling the supply means including a control device and an expandable chamber operating means operably connected to the control device, said control means having an inherent operating differential, means including a main thermostat bulb connected to the operating means and responsive primarily to the temperature of the medium in said enclosure for controlling said cyclical control means, and means including a smaller thermostat bulb connected to the operating means, said smaller bulb being cooled by said cooling unit and being so small in relation to the main bulb and the amount of change in volume of the operating means required to operate the cyclical control means as to be incapable alone of operating the cyclical control means for reducing the inherent differential of the cyclical control means.

GEORGE C. PEARCE.
ALBERT O. GROOMS.
